UNITED STATES PATENT OFFICE.

JOSEPH BERGE, OF MONTCLAIR, NEW JERSEY.

CAP.

Application filed March 19, 1925. Serial No. 16,647.

My invention is of a cap or capping ring. The cap or capping ring of my invention has many uses, among which may be mentioned as examples, receptacles, open cylinders, cups, cases, bottles, cisterns, instruments, clocks, etc.

When the device is continuous, I preferably refer to it as a cap. The same device with an opening therein I refer to as a capping ring. The mode of attachment is the same in each case. For convenience of expression I may use the term cap as the generic expression to include both.

The cap, which is of hard and strong material, preferably metal, is provided with a flange to encircle the body of whatever article, container, casing, cylinder, etc., is to be capped.

This flange is inturned at its margin, the inturned part making an acute, through not necessarily sharp angle, with the remaining portion of the flange.

The opening within the inturned margin is slightly smaller than the outer diameter of the body to be capped. The cap having the flange with the inturned margin is forced on to the body to be capped, the inturned marginal part springing or yielding slightly to permit the cap to pass over the body.

The inturned margin has a sharp edge or corner where it contacts with the body. The material of the body if smooth is preferably somewhat softer than the cap material so that the marginal edge or corner can "bite" into the material of the body or the body may have grooves rolled into it, so that the sharp cap margin edge will engage these grooves.

When the cap is in place it is self-locking, and any force or pressure applied to remove it merely causes tighter and closer engagement of the cap with the body, so that a permanent closure is effected, and to take the cap off it must be destroyed. Thus by a very simple and cheap construction I am enabled to permanently close bodies, casings, etc., and to prevent objects or instruments therein from being tampered with.

The accompanying drawings show embodiments of the invention for purposes of illustration and affording an understanding of the invention, but without imposing limitations thereon.

In the drawings, Fig. 1 is a part section and part side view of a body with a cap in place thereon. Figs. 2, 3 and 4 are sectional

details showing the mode of application of the cap of Fig. 1. Fig. 5 is a detail section of a cap on a serrated body, and Fig. 6 is a detail section of a capping ring holding a disk on a smooth body.

The preferably cylindrical casing 10 may be smooth on its exterior or may be roughened or serrated, as shown in Fig. 5, by having the serrations or grooves 11 formed therein, preferably by rolling them in. When so serrated the grooves 11 preferably have comparatively sharp downwardly directed corners or edges 12, which serve to prevent a cap engaged therewith from being pulled off.

The cap of Figs. 1-4 designated generally by reference numeral 13 comprises the closure part 14, the flange 15, and the flange margin inturned portion 16, having the sharp edge 17.

The angle 18 between inturned part 16 and flange part 15 is decreased somewhat as indicated (exaggerated) at 18', Fig. 4, when the cap is applied and forced down over the body from the position shown in Fig. 3 to that of Fig. 4. If force is applied with the intention of removing the cap, the fact that the inturned margin 16 is reversely turned with respect to the flange portion 15 causes the former to "dig in" or lock. Thus the cap or its flange must be destroyed in order to permit removal.

The capping ring 19 of Fig. 6 has a central opening 20. When using such capping rings with either a smooth walled or a serrated body, a disk 21 of metal, glass, paper or any other material may be inserted between the body and the capping ring and held in place by the latter and same cannot be removed without practically destroying the capping ring. When used in connection with clocks, gauges, instruments and the like, the member 21 consisting of the face or dial of such clock, gauge or instrument is held in place by the capping ring 19.

It will be seen that the invention affords a very simple and cheap construction, especially well adapted for sheet metal structures in which it is desired to permanently cap an open ended body with a cap to remain permanently in place, and which will resist removal until it is itself destroyed.

I claim:

A cap for a body provided with external threads or serrations adjacent the end to be capped, said cap having a flange with a re-

versely inturned preformed margin terminating in a sharp edge, the opening within the inturned margin being of diameter slightly smaller than the outside diameter of 5 the body end to be capped, so that the sharp edge of the cap margin, on being forced over the body, engages the furthermost of the threads or serrations and grips same

with a grip which is increased by application of force in a direction to retract the cap, and the cap resists removal until it is itself destroyed.

In testimony whereof, I have signed my name hereto.

JOSEPH EERGE.
